UNITED STATES PATENT OFFICE

163,761

RANGE

Michael J. Maier, Beaver Dam, Wis., assignor to
Malleable Iron Range Company, Beaver Dam,
Wis., a corporation of Wisconsin

Application May 12, 1949, Serial No. 2,602

Term of patent 14 years

(Cl. D81—4)

To all whom it may concern:

Be it known that I, Michael J. Maier, a citizen of the United States, residing at Beaver Dam, in the county of Dodge and State of Wisconsin, have invented a new, original, and ornamental Design for a Range, of which the following is a specification, reference being had to the accompanying drawings, forming a part thereof, in which:

Fig. 1 is a front elevational view of a range, showing my new design;

Fig. 2 is a top plan view thereof; and

Fig. 3 is an end view thereof.

The dominant features of the design reside in the portions shown in full lines.

I claim:

The ornamental design for a range, substantially as shown and described.

MICHAEL J. MAIER.
